UNITED STATES PATENT OFFICE.

ISAAC B. KLEINERT, OF NEW YORK, N. Y., ASSIGNOR TO THE I. B. KLEINERT RUBBER COMPANY, OF SAME PLACE.

DESIGN FOR A DRESS-SHIELD.

SPECIFICATION forming part of Design No. 26,757, dated March 16, 1897.

Application filed April 18, 1896. Serial No. 588,188. Term of patent 14 years.

To all whom it may concern:

Be it known that I, ISAAC B. KLEINERT, a citizen of the United States, residing at New York city, in the county of New York, State of New York, have invented and produced a new and original Design for Shields, of which the following is a specification, reference being had to the accompanying drawings.

My design is clearly shown in the accompanying drawings, in which—

Figure 1 is a perspective view of a shield made according to my design. Fig. 2 is a side view of the same.

The leading feature of my design consists in such a shape of the shield that two extended wings are formed on the front portion thereof, leaving a substantially V-shaped opening between said two wings, the point of the V terminating at the front of the upper concave curve, as shown in the drawings. The outline of each side or flap of the shield

has an extended point in the rear at the junction of the concave and convex curved lines of the top and rear edges of said flap, and a convex edge in front, which runs backward ²⁵ nearly one-third of the length of the shield to the junction of the two flaps, thus forming one of the wings before referred to as being on each side of the V-shaped opening. I have shown the edges scalloped or "pinked," ³⁰ but this may be left off without changing the essential feature of my design.

What I claim as new is—

The design for a shield, substantially as shown and described.

In testimony whereof I affix my signature, in the presence of two witnesses, this 17th day of April, 1896.

ISAAC B. KLEINERT.
